LOG GROOVER

Dennis W. Merrill, Albany, Oreg.

Application June 11, 1947, Serial No. 753,831

4 Claims. (Cl. 144—136)

1

This invention relates to improvements in log grooving apparatus.

An object of the invention is to provide an improved log grooving apparatus which will form spaced parallel longitudinally extending grooves along the diametrically opposed sides of logs.

Another object of the invention is to provide an improved log grooving apparatus which will simultaneously cut spaced parallel longitudinally extending grooves along the diametrically opposite sides of logs for receiving chinking boards used for tying or securing adjacent boards or logs together when constructing log buildings and structures.

A further object of the invention is to groove peeled and seasoned logs or poles for use in building construction by precision machinery that will eliminate much hand labor in joining logs into wall construction and eliminate the problem of log taper so that a building's level and plumb angles may be easily maintained in the process of construction.

Another object of the invention is to provide a precision machine for grooving logs which will receive logs rolled from the storage log deck onto suitable rollers where they may be adjusted for endwise positioning if necessary, and from thence the logs will be rolled onto lifting arm bunks where suitable blocks will convey each log to the center of the bunk by suitable power driven means, to be raised by a hydraulic jack until centered, after which toothed heads will engage the center points at the opposite ends of the log, and finally the log carriage upon which the log is supported will carry the log along the channel cutting saws or knives which would be spaced to cut the desired depth channel or channels on both the upper and lower sides lengthwise of the log.

Another object of the invention is to provide an improved log grooving apparatus which will be highly efficient in operation, and relatively inexpensive to manufacture and produce.

Other objects will appear as the description proceeds.

In the accompanying drawings which form a part of this application,

Figure 1 is a side elevation of the log carriage with a log supported in position thereon;

Figure 2 is a plan view of the lift carriage rails and log carriage rails with a log supported between two log blocks, and showing the electric motor driven means for operating the same;

Figure 3 is a side elevation of the improved log centering and lifting apparatus;

2

Figure 4 is a partial sectional view taken on the line 4—4 of Figure 3;

Figure 5 (Sheet 2) is a detailed sectional view taken on the line 5—5 of Figure 3;

Figure 6 is a top plan view partly broken away of one of the log blocks;

Figure 7 is a front elevation of the protractor used when changing the angular position of the logs in the blocks;

Figure 8 is a front elevation of the log grooving cutters or saws;

Figure 9 is an enlarged detail view of the drive gearing for operating the log blocks;

Figure 10 is a transverse sectional view through several grooved logs showing the same connected together by chinking boards, and

Figure 11 is a plan view of a log showing the spaced parallel longitudinal grooves formed in its surface.

20 Like characters of reference are used throughout the following specification and the accompanying drawings to designate corresponding parts.

In carrying out the invention, there is provided 25 an elevated track comprising the rails 1 and 2, and a lower track comprising the rails 3 and 4 extending parallel with said first mentioned elevated track and spaced slightly to the side thereof. The rails 1 and 2 will be supported upon the heavy wood bolsters 5 and 6 (Fig. 4) while the rails 3 and 4 are supported upon the lighter wood bolsters 7 and 8.

A log deck 9 is disposed along the lower track rails 3 and 4 in parallel relation thereto, whereby 35 the logs 10 which are to be grooved will be rolled from the log deck 9 onto suitable rollers 11 disposed at the inner ends of the two spaced lift carriage frames 12 which are mounted upon the supporting wheels 13 and 14 (Fig. 3) for longitudinal movement along the rails 3 and 4, there 40 to be adjusted for endwise position if necessary.

From the rollers 11, the logs 10 will be rolled onto the lifting arm bunks 15 (Fig. 4) supported on the outer ends of the bellcrank lifting arm 45 16.

Each log bunk 15 is provided with a screw 17 upon which a pair of centering blocks 18 and 19 are adjustably supported for inward or outward movement as the hand operating crank 20 secured to the screw 17 is rotated in one direction or in the reverse direction. When the blocks 18 and 19 are adjusted to touch either side of the log 10 while it rests upon the bunk 15, the log will 50 be in horizontally centered position.

It will be understood that a second lift carriage 55 (not shown) similar to the carriage 12 will be

provided and would be reversed in direction in order to face the end of the log 10, also the carriage wheels and axles (not shown) would be reversed so the carriage would move sidewise at right angles to the log carriage tracks 3 and 4, to ride on the rails 21 and 22 in order that the second carriage (not shown) may be pulled back a few inches after the log 10 has been raised to allow proper clearance for the log and log block.

Each lift carriage 12 will support the spaced vertically extending supporting standards 23 and 24 between which the lift arm 16 is pivotally mounted on the cross shaft 25.

A hydraulic jack 26 is supported upon each carriage frame 12 and is connected by means of a hydraulic oil line or hose 27 with a supply of oil under pressure suitably connected therewith, but not being illustrated. The piston rod 28 of the jack 26 will be pivotally connected at 29 to the lifting arm 16.

A square edge shaft guide 30 will be supported by the standards 31 mounted upon the carriage 12, extending in a horizontal plane and slidably supporting the sleeve guide 32 to which the upper and lower connecting bars 33 and 34 are pivotally connected. The connecting bars 34 will be pivotally attached at 35 to the upper end of the bell-crank lift arm 16.

The bellcrank centering arm 36 will be disposed above and in vertical alignment with the lift arm 16, and will be pivotally supported upon the cross shaft 37 disposed between the inverted U-shaped frame 38 attached by the bolts 39 to the standard 24. The inner end of the centering arm 36 is pivotally connected at 40 with the end of the upper connecting rod 33. An adjustable contact member 41 is supported upon the lower side and at the end of the centering arm 36 for engagement with the upper surface of the log 10. When the lifting arm 16 raises the log 10 to a point where the member 41 touches the top of the log, the log will be centered vertically and the log blocks 42 and 43 later to be described, may be closed enough to engage each end of the log 10.

The log blocks 42 and 43 (Figs. 1 and 2) are supported by the frames 44 (Figs. 4 and 8) secured upon the log carriage generally designated by the reference numeral 44' composed of the longitudinally extending I-beams 45 connected together by the spacing bars 46 for permitting sawdust to escape. An I-beam track comprising the spaced longitudinally extending I-beams 47 and 48 is disposed upon the log carriage 44' and supports the log blocks 42 and 43 through frames 44 upon their upper flanges, being secured by the flange members 49 and 50, while a strap iron strip 51 (Fig. 8) is provided for closing the space between the carriage frame I-beams.

Each log block 42 and 43 includes a shaft 52 disposed longitudinally thereof and is formed with a toothed head 53 on its inner end, and a protractor 54 with indicating pointer 55 (Figs. 3, 6, 7 and 8) on its outer end for determining the degree of rotation when the log 10 supported between the toothed edges 53 is rotated. A gear 54' is secured to the shaft 52 and is connected with the reduction gearing 55', which will be operated by the hand crank wheel 56 for turning the log 10 to the desired angle for cutting one or more grooves longitudinally in the log at any point or points in its circumference. A brake drum 57 will be supported by the shaft 52 and will be engaged by the brake shoe 58, the same be-

ing applied and released by means of the ratchet hand levers 59 and interconnected linkage 60.

In operation of the log blocks 42 and 43, the same will be moved into position for the toothed heads 53 to engage and support a log 10 when disposed therebetween. If the log has to be turned, it will be accomplished by rotating the hand crank 56, which in turn will operate through the reduction gear train 55' to rotate the shaft 52 and the log 10. When the log is in the desired position, the ratchet hand brake applying lever 59 will be operated to set the brake shoe 58 against the brake drum 57, thereby locking the several parts in fixed position.

The log carriage 44' is supported for longitudinal movement upon the rails 1 and 2 by means of the series of wheels 61 which are flanged as at 62 on their opposite edges to retain the same upon said rails, said wheels being rotatably mounted upon the stub axles 63 supported below the log carriage 44'.

The log blocks 42 and 43 are provided with threaded nuts or bearings 64 formed as parts of their frames 44, through which the aligned operating threaded screws 65 and 66 are rotatably extended. The screws 65 and 66 are rotatably mounted in the bearings 67 and 68, and support the bevel gears 69 and 70 on their adjacent inner ends. See Fig. 9. The gears 69 and 70 are connected with the reduction gears 71 which in turn are driven by a friction wheel 72. A slideable shaft 73 supporting friction pulleys 74 and 75 is driven through the gearing 76 (Figs. 2 and 4) by an electric motor 77, and is controlled by an actuating bearing 78. The electric motor 77 and friction pulleys and gearing are attached to and supported upon a platform 79 secured to the log carriage 44'.

A cable 80 is attached to an eye 81 at one end 40 of the log carriage 44' and will extend over an idle pulley 82 at one end of the tracks 1 and 2 and will be connected with a cable drum (not shown) located midway of the tracks 1 and 2, and from thence to a cable pulley (not shown at the other ends of the tracks 1 and 2, and back to connect with the eye 82 at the other end of the log carriage 44'). The cable drum would be driven in any desired manner, as for example, by a reversible friction pulley arrangement (not shown) and controlled by a log carriage operating lever (also not shown) located midway of the length of the tracks 1 and 2.

In Figure 3, there is illustrated a pair of upper and lower channel grooving saws or knives 83 and 84 for forming a single channel in each of the upper and lower edges of a log. Obviously, if two parallel grooves or channels were to be cut in the logs, the second saw or knife would be secured upon each saw supporting shaft 85 and 86, which are disposed at the near side of the tracks 3 and 4 when viewed in Figure 1 of the drawings, while the lumber cutting saws (not shown) would be disposed on the far side of the tracks. A rotary saw 87 will be mounted on a driven shaft 88 for cutting off slabs from the log 10 to provide a level surface on the logs if desired, for the purpose of a lath and plaster or wallboard finish. The same procedure would apply where the logs are used as joists for flooring purposes. Also, the top sides of rafter poles would be flattened parallel to the taper, this operation being completed on the sawmill side of the log carriage 44'.

From the foregoing description, it will be apparent that when the logs 10 are correctly posi-

tioned and locked between the toothed heads 53 on the log blocks 42 and 43, the lift carriage 12 would be rolled back out of the way, and the log carriage 44' would be moved along the tracks 1 and 2 to carry the log 10 between the channel cutting saws or knives 33 and 34, which would be spaced to cut the desired depth channel on both the upper and lower sides longitudinally of the log 10. The channels may be cut at any desired angle by merely rotating the log in the log blocks in the manner hereinbefore described.

Finally, the logs would be sorted into diameter and length classifications for each specific purpose that each classification is to be used, thus providing for all the necessary amount of a particular classification to be run at one setting so that the machine would not have to be set up so often for log size adjustment.

While the preferred embodiment of the instant invention has been illustrated and described, it will be understood that it is not intended to limit the scope of the invention thereto, as many minor changes in detail of construction may be resorted to without departure from the spirit of the invention.

Having described the invention what is claimed as new is:

1. A log grooving apparatus comprising laterally spaced pairs of parallel track rails, a pair of wheel supported log lift carriages movably mounted in opposed relation to each other on one pair of said rails, said carriages being adapted to support the opposite ends of a log, each of said carriages including a bellcrank lever pivoted at its corner, a pair of log receiving centering blocks mounted on one leg of said lever, means for adjustably moving said centering blocks towards and away from each other, a toothed gripping member mounted on said carriage and adapted to engage an end of a log, means for pivoting said bellcrank lever to raise the log into a position so that an end thereof opposes said gripping member, means operatively connected to and cooperating with said bellcrank lever to hold the log in said position, means for urging said gripping member out of and into engagement with the end of the log, a second carriage including a grooving saw and mounted on the other pair of said rails, and means for moving said second carriage whereby said saw engages one side of the log to produce a longitudinal groove therein.

2. The combination of claim 1 and a means for adjustably rotating said gripping member through a predetermined angle.

3. The combination of claim 1 wherein said third-named means includes a shaft, a collar

slidable on said shaft, a link terminally pivoted to said collar and to the other leg of said bellcrank, a further bellcrank pivoted at its corner to said carriage and disposed above said first bellcrank, an adjustable log contacting member carried by one leg of said further bellcrank, and a link terminally pivoted to said collar and to the other leg of said further bellcrank.

4. A log grooving apparatus comprising laterally spaced pairs of parallel track rails, a pair of wheel supported log lift carriages movably mounted in opposed relation to each other on one pair of said rails, said carriages being adapted to support the opposite ends of a log, each of said carriages including a bell crank lever pivoted at its corner and including log receiving jaws at the end of one of its legs, means for pivoting said bell crank lever to raise the log received on said jaws, a toothed gripping member mounted on said carriage, means operatively connected to and cooperating with said bellcrank for vertically centering the log to be in alignment with said gripping member, means for urging said gripping member out of and into engagement with the end of the log, a second carriage including a grooving saw and mounted on the other pair of said rails, means for moving said second carriage whereby said saw engages one side of the log to produce a longitudinal groove therein, and means for adjustably rotating said gripping member through a predetermined angle, said last-named means including a shaft secured to said gripping member and rotatably journaled on said carriage, a crank wheel for rotating said shaft, an indicating device carried by said carriage adjacent said crank wheel, and a brake for holding said shaft against rotation at a desired angle of rotation.
